UNITED STATES PATENT OFFICE.

JOSEPH M. WEINGAERTNER, OF NEWARK, NEW JERSEY, ASSIGNOR TO TOLEDO CHAMBER OF COMMERCE, OF TOLEDO, OHIO, A CORPORATION OF OHIO.

DESIGN FOR AN EMBLEM.

40,238.

Specification for Design.

Patented Aug. 31, 1909.

Application filed June 28, 1909. Serial No. 504,948. Term of patent 7 years.

To all whom it may concern:

Be it known that I, JOSEPH M. WEINGAERTNER, a citizen of the United States, residing at Newark, in the county of Essex and State of New Jersey, have invented a new, original, and ornamental Design for an Emblem, of which the following is a specification, reference being had to the accompanying drawing, forming a part hereof.

The figure is a face view of the emblem, showing my new design.

I claim:

The ornamental design for an emblem as shown.

JOSEPH M. WEINGAERTNER.
